UNITED STATES PATENT OFFICE

EMANUEL SCHÄFER, OF DUSSELDORF, GERMANY, ASSIGNOR OF ONE-HALF TO EMIL FLECHTHEIM, OF DUSSELDORF, GERMANY

INTERNAL-COMBUSTION ENGINE

Application filed April 13, 1928, Serial No. 269,818, and in Germany February 18, 1926.

My invention relates to an internal combustion-engine with the cylinders disposed like chords, the pistons, fitted each with a driving roller, effecting the revolution of the cylinders through the intermediary of a cam-track.

By this invention a simple construction of an internal combustion-engine is obtained which is easy of access and in which all elements are very practically arranged and in which the dimensions are so favorably selected that maximum efficiency and reliability are obtained as well as minimum weight.

15 The novel feature consists in that the cylinders together with the positively guided pistons are accommodated in pairs in a rotor of limited dimensions, the admission and exhaust being controlled by a single valve which is cooled by the inflowing gas-mixture, the admission and exhaust-ports of said valve being sealed approximately free from friction. This sealing of the admission and exhaust ports is effected by concentric faces 20 narrowed to the width of the port or by a stationary cylindrical body of small diameter, which is sealed after the manner of a piston. The pistons are positively guided by two rollers and double cams and by driven 25 30 slideable plates.

Several embodiments of the invention are shown, by way of illustration, in the accompanying drawing in which:—

Fig. 1 shows an engine provided with two 35 cylinders taken in a vertical section along line 1—1 in Fig. 2.

Fig. 2 is a cross-section along line 2—2 in Fig. 1.

Fig. 3 is a section along line 3—3 in Fig. 40 2 taken in front of the rotor.

Fig. 4 is a section through a modification. Fig. 5 is an end elevation and

Fig. 6 a side-elevation showing a four-cylinder engine with bodies on the end-face serving for the admission and exhaust.

Fig. 7 shows partly in elevation and in the other half in section along line 7—7—7—7 in Fig. 9 the inner construction of the engine.

50 Fig. 8 is a section along line 8—8—8—8

in Fig. 9, the admission and exhaust-bodies being shown at the left end of the figure in a separate view.

Fig. 9 is a sectional view, the section being taken along line 9—9 in Fig. 7.

Fig. 10 is a section through the rotor without piston along line 10—10 in Fig. 9.

Fig. 11 shows in elevation and

Fig. 12 in top plan view, partly in section the arrangement of a double admission- and 60 exhaust-body between two rotors.

Fig. 13 is a section through the lower end of the piston on a larger scale.

Fig. 14 is a section along line 14—14 in Fig. 13.

65 In a casing 1, composed of several parts and a cylindrical cross-section, a cylindrical rotor 2 is rotatably mounted containing two cylinders 3 arranged like chords, the two cylinders being so disposed that they cross 70 one another when two pairs of cylinders are provided. The rotor 2, together with the engine-shaft 4 fixed therein, is centrally mounted within the closed cam-track 5 of casing 1 and designed to guide the pistons 75 6 mounted in the cylinders 3. The diameter of the rotor 2 is smaller than the inner diameter of the casing when the cam portions of the cam-track project farthest into the casing. Each cylinder 3 being closed at one 80 end forms, together with the pistons 6, the combustion chamber 7. At the open end of each cylinder 3 an extension 8 is provided which projects beyond the circumference of the rotor so that the corresponding piston 85 6 will have a long stroke to completely utilize the expansive effect of the gases in the combustion chamber 7. At the open end of each cylinder 3 an extension 8 is provided which projects beyond the circumference of the rotor so that the corresponding piston 85 6 will have a long stroke to completely utilize the expansive effect of the gases in the combustion chamber 7. The admission of the explosive-mixture as well as the exhaust of the burnt gases are controlled by a single 90 valve 10 operated by an inclined cam 9, said valve making the combustion-chamber communicate alternately with the admission port 13 and with the exhaust port 14 by means of slots 11 and 12 respectively. The valve is 95 therefore alternately exposed to the action of fresh cool gases and hot exhaust gases, so that, after each heating, the valve is cooled again with the result that by the utilization of the inflowing explosive-mixture as cooling 100

medium the life of valve 10 is considerably lengthened.

The sealing between the combustion-chamber and the admission and exhaust-ports, the construction of the admission- and exhaust-passages and the guiding of the pistons may be accomplished in different ways.

As shown in Fig. 2 the sealing consists of a concentric sliding ring 15 provided on the rotor 2, which ring is guided tightly packed in a concentric ring-groove 16 secured to the casing 1; while the sliding ring 15 has only two short slots 17 leading to the combustion-chamber 7, the ring-groove 16 has two longer slots 11 and 12 along which the two slots 17 move. With the long slots 11 and 12 communicate the admission- and exhaust-ports 13 and 14, enlarged towards the middle. As the rotor rotates, the slots 17 alternately serve for the admission of gas as the admission-slot 11 moves past the same and for the exhaust of the burnt gases, as the exhaust-slot 12 moves past them. The admission and exhaust are thus successively effected, the valve 10 being open, as its cam-roller 18 rolls up on the inclined bar 9. During the compression and explosion, valve 10 is maintained closed as usual by the action of a spring 19.

In the construction shown in Figs. 1 to 3 the ignition is effected by a spark plug 20 projecting, opposite the valve 10, into the combustion chamber 7 and coming in contact with a contact 21 on the casing. The contact 21, designed for advanced and retarded ignition, is constructed like a double-contact and comprises two contacts 21^a and 21^b (Fig. 2) spaced apart a certain distance and designed to be touched by the ignition-pin of the spark plug 20, current being alternately supplied to said contacts by a contact-lever 23, pivotable around a pivot-pin 22. The contact-lever 23 may be reversed from the driver's seat in any suitable manner.

In all the constructions, except the one shown in Fig. 4, the cam-track 5 is situated in the direction of the axis of the cylinders. The reciprocating movement of the pistons 6 is controlled by the rollers 24 rolling on the inner edge of the cam-track 5. Their positive movement is attained, according to Figs. 1 to 3, by a second cam-track 25 secured to the casing at the side of the rotor 2, a second roller 27, also mounted on the bolt 26 of the roller 24, running on the outer edge of said cam-track 25. Bolt 26 slides in a longitudinal slot 28 of the extensions 8, a control slot 29 of said extensions engaging over the cam-track 5.

A portion 30 of the wall of the casing and of the cam-track is removably or hingedly connected, as shown in Figs. 1 to 3, to make the mechanism of the engine accessible.

Two such removable or hinged portions 30, 65 one for each pair of cylinders, are provided

in a multicylinder engine as shown in Figs. 4 to 12. Through the openings formed by the removal of these portions 30, all the inner elements of an engine, with the exception of the rotor, can be removed, so that it is no longer necessary to take the engine to pieces for replacing one or the other element.

In all the constructions the cooling of the cylinders 3 is effected through the intermediary of the engine-shaft 4 which is hollow, with the exception of the portions in the centres of the cylinders which are solid, said hollow shaft communicating, on the one hand through an inlet 31 and on the other hand through an outlet 32, with the cooling spaces 33 of the rotor 2. In an engine having more than three cylinders 3, as shown in Figs. 5 to 12, the admission and the exhaust of the gas mixture and of the burnt gases respectively are preferably effected through the intermediary of admission and exhaust passages 34 and 35 extending in axial direction from one end face of the rotor 2, the rear ends of said passages terminating in the valve chambers 36 and the front ends terminating radially into a cylindrical cavity 40. During one rotation of the rotor 2 the radial mouths of all the passages move successively along a common admission slot 37 and along a common exhaust slot 38, arranged in a stationary cylindrical body 39 and beginning in the end face and terminating in the circumference of said body. The rotor 2 rotates around its own axis and around the axis of the body 39. This body is secured to the casing 1 and gas-tightly mounted in the cylindrical cavities 40, arranged in the end face of the rotor, by means of packing-rings and bars 41 and 42, so that friction is produced only on the packing faces and losses through friction are almost excluded owing to the small diameter of the body 39. By the channels 34, 35 moving along the stationary admission slot 37 and exhaust slot 38 of the body 39, the admission and exhaust for the several pairs of cylinders 43, 44 and so forth, which in four cylinder engines are arranged cross-wise and in six- and more cylinders star-shaped around the engine axis, are successively effected so that, while one cylinder exhausts the burnt gases the next following cylinder is charged with fresh gas, and so forth. While the channels 34 as shown in Figs. 9 and 10 terminate at the rear end in the valve chamber 36 of the first group of cylinders 43, the channels 35 move along the row of cylinders 43 to the valve chamber 36 of the cylinders 44 of the second group.

According to Figs. 4 to 10 a body 39, together with carburetor 45, effects the admission and exhaust from the end face of the rotor 2. As shown in Figs. 11 and 12 a double body 46 together with a carburetor regulates the admission and exhaust, said

double body being mounted between the two groups of cylinders 43 and 44, which are arranged in two separate rotors 2 and 2^a, the gas-admission and the exhaust of the burnt gases taking place through main passages 47, 48, at either side of which the admission-slot 37 and exhaust-slot 38 are arranged. To the main passage 47 the carburetor is connected, the passage 48 communicating with the atmosphere.

The positive guiding of the piston 6 is effected, according to Fig. 4, by slidable plates 57 which, in the segment of the rotor 2 parallel to the cylinder axis, are connected to the piston 6, their two ends 58 and 59 displaced the one with regard to the other in the direction of the axis of rotation and both constructed to act as running surfaces moving in two curves 60, 61 arranged one at the side of the other. The slidable plates 57 are located in borings 62 arranged parallel to the cylinders 3 and they are each connected by an arm 63 to the piston 6, said arm sliding in a longitudinal slot 58'. The curves 60, 61 are preferably formed by grooves arranged in the casing 1.

The cam-track 5 for the pistons 6 is subdivided into four sections which, as shown in Figs. 1 to 8, are of unequal length and of unequal curvature or, as shown in Figs. 11 and 12, of equal length and similar curvature. By the longer sections an exhaust- and suction-stroke, longer with regard to the compression and explosion curve is produced, while with the sections of equal length all strokes are of the same length.

The operation of the engine is as follows:

After the rotor 2 has been started, and the driving roller of one of the pistons 6 has arrived on the point 5^a of the cam-track 5, an explosion occurs, through which the rotor 2 is rotated. The corresponding valve 10 is closed and opens again only at point 5^b of the cam-track 5 respectively after the expansion power of the burnt gases in the combustion chamber 7 have produced their complete effect. In the following section 5^b to 5^c the piston is pushed into the cylinder 3, the valve 10 being open, whereby the burnt gases are expelled through valve 10 and through the exhaust 14 or 46 respectively. In the section 5^c to 5^d the piston is moved out of the cylinder, the valve 10 being now open, and it consequently sucks in a gas-mixture which cools valve 10. The gas is compressed in the section 5^d to 5^a by the inward movement of the piston, the valve being closed and ignited again at 5^a and so forth. The other pistons 6 perform in a similar manner as this piston, whether the engine is a two-cylinder engine, or a four or more cylinder engine, the working stroke at 5^a, whereby a rotating impulse is exerted upon the rotor twice, four or more times, and the pistons successively effect also the ex-

haust, intake and compressing. Since rotor 2 acts as centrifugal mass, it is not necessary to provide a fly-wheel.

I claim:

1. An internal combustion engine, comprising an outer casing formed with a cam-track along its inner wall, a shaft journalled in said casing, a cylindrical rotor secured to said shaft and containing cylinder bores tangential relative to said shaft and disposed in the same plane, a reciprocating piston provided in each of said bores, a roller provided at the outer end of each piston and adapted to come in contact with the cam-track of said casing, a single admission and exhaust valve at the inner end of each cylinder bore, a body located in a central recess of said rotor and having passages adapted to communicate with ports in said valves so as to control the supply of fresh explosive-mixture and the exhaust of the burnt gases, and means in said casing for operating said valves in timed succession.

2. An internal combustion engine, comprising an outer casing formed with two adjacent cam-tracks along its inner wall, a cylindrical rotor rotatably mounted in said casing, cylinder bores provided in said rotor disposed like chords, a positively guided piston in each cylinder bore, a continuous slidable plate in each piston extending along the chord of said rotor parallel to the axis of the cylinder bore and having its end in contact with said cam-tracks, a single admission and exhaust valve for each cylinder bore arranged to be cooled by the inflowing explosive mixture and provided with an admission and exhaust passage, and packings for sealing said passages substantially frictionless.

3. The combination as specified in claim 2, including a cam portion on the inner wall of said casing for operating said valves.

In testimony whereof I affix my signature.

EMANUEL SCHÄFER.
